UNITED STATES PATENT OFFICE.

CARL J. WITZORECK, OF MILLVALE, PENNSYLVANIA.

ACQUAINTANCE-PROMOTING MACHINE.

1,329,218.

Specification of Letters Patent. Patented Jan. 27, 1920.

Application filed June 13, 1918. Serial No. 239,905.

To all whom it may concern:

Be it known that I, CARL J. WITZORECK, a citizen of the United States, and a resident of Millvale, in the county of Allegheny and 5 State of Pennsylvania, have invented a new and Improved Acquaintance-Promoting Machine, of which the following is a full, clear, and exact description.

This invention relates to a machine adapted to be used in confectionery and other stores, ice cream parlors and the like, for the running of acquaintance-promoting clubs, the members of which will have some suitable designating device, such as a button of a particular color, for a given city or locality, and a designating number or letter, the letter being the designation of the machine or club and the number the membership designation thereof. Each member has 15 the privilege of addressing communications to any member of any other club by taking note of the color of the button, the letter and number thereon and correspondingly addressing the communication which is 20 dropped in the home machine and mailed by the owner of the latter, and the addressee will reply and address his or her communication with the machine and membership designation of the first person. 25 The general objects of the present invention are to provide a machine for the purpose mentioned which is of comparatively simple and inexpensive construction, easy to operate, and reliable and efficient in use, 30 said machine embodying a cabinet having a plurality of drums for holding photograph-bearing cards and means for operating or adjusting the drums with respect to the view opening, also a rack containing membership pigeonholes for cards, letters or other communications, and means for holding cards or writing materials for the members to use. 35

For a more complete understanding of 40 the invention reference is to be had to the following description and claims taken in connection with the accompanying drawings, which illustrate one embodiment of the invention and wherein similar characters of reference indicate corresponding parts in all the views, in which

Figure 1 is a front view of the machine with portions broken away to illustrate the details of construction;

Fig. 2 is a vertical section; Fig. 3 is a side view;

Fig. 4 is a rear view of the upper portion with the door of the pigeonhole box open;

Fig. 5 is a fragmentary edge view of a drum;

Fig. 6 is a fragmentary view of the circumference of the drum;

Figs. 7 and 8 are views of a photograph;

Figs. 9 and 10 are views of the membership buttons;

Fig. 11 is a detail sectional view on the line 11—11, Fig. 1; and

Fig. 12 is a view of a notification card.

Referring to the drawing, A designates a cabinet which is of any approved construc-

tion or design, and in the top 1 is a view opening 2 through which members of the acquaintance club having the machine are privileged to look to see photograph cards which may have been received for them.

Within the cabinet is a horizontal shaft 3 on which is slidably mounted and keyed thereto a drum d made of two sections 4 and 5 connected by a hub collar 6, and the periphery of each section has fastened thereto parallel strips 7, so arranged that between adjacent strips a pocket will be formed for receiving a plurality of photograph cards which are exchanged between members of the same club or of different clubs.

These pockets are numbered from 1 to 50 on one section and from 51 to 100 on the other section, and besides the number each pocket has a letter which corresponds to the letter assigned to the whole machine.

Thus, as shown in Fig. 1, the machine is lettered A. The shaft 3 has an extension 3^a which projects out of the cabinet and is pro-

vided with an index wheel 8 which on its periphery has a band 9 which bears numbers to correspond with the pocket numbers on the drum d. This wheel 8 is fastened to the shaft, so that when the wheel is turned the drums turn with it. On the projecting end of the shaft 3 is a loose arm 10 which

has a handle 11 formed with a pin 12, which slides through the eye-like extremity 13 of the arm, so that the pin can be engaged in any one of the apertures 14 arranged in the side face of the wheel 8, there being fifty

of these apertures to correspond with the number of pockets on the drum, and behind the wheel is a stationary locking member 15 having an aperture 16 into which the pin 12 engages, so as to hold the drum stationary, with the desired card-holding pocket thereof in alignment with the view slot 17

in a scene plate 18 arranged in the top of the cabinet at a point between the drum and view opening 2.

The slot 17 is as long as either section 4 or 5 of the drum is wide, and consequently it is necessary to shift the drum axially to bring the pocket of any drum into registry with the slot 17. For this purpose a shifting arm 19 is mounted on a rock shaft 20 and has a bifurcated end 21 which straddles a ring 22 mounted in the groove 23 of the hub extension 24 of the drum section 5, there being pins 25 on the ring 22 which engage in slots 26 in the bifurcations 21. The shaft 20 extends out of the rear of the casing and has an operating handle 27 whereby the owner or person in charge of the machine can shift the drum for the purpose mentioned. When the drum is shifted to either of its extreme positions from the normal central position shown in Fig. 1, an electric lamp 28 in the top of the cabinet is adapted to be lighted to illuminate the scene plate 18, this lamp being connected in a circuit 29 having a source of current 30 and stationary contacts 31 and 32 with which is adapted to engage a contact 33 carried by the lever 19, so that automatically the switch composed of the parts 31, 32 and 33 will close the lamp circuit when the drum is in either of its extreme positions. The contacts 31, 32 are mounted on a plate 30^a which is provided with a clamping bolt 30^b that extends through a slot 30^c in the wall of the cabinet, so that the contacts 31, 32 can be adjusted with respect to the contact 33.

In the bottom of the cabinet is a box 34 to which leads a drop chute 35 having an opening 36 at the top of the cabinet, so that any member can drop a card or other communication into the cabinet, which communications are collected at stated times by the one in charge of the machine and delivered or mailed.

At the top of the cabinet is a case or rack B which is divided into pigeonholes 37 which are closed at the front by a glass 38 which has designations from A-1 to A-100, there being a pigeonhole for each member of the correspondence club. On the back of the case B is a door 39 which has a plurality of holders 40 of any suitable construction for holding cards, letter paper, envelopes and the like for the members to use.

Each member has a button C which bears a club letter c, Fig. 9, and a membership number c', the button in Fig. 9 belonging to a member of club A and having the membership designation 25. Other clubs in the same city would have buttons of the same number but different letters or combinations of letters, and members of clubs in other cities would have buttons of different colors, 65 as the button D in Fig. 10.

Each member of a machine will be provided with photo-cards F, such as shown in Figs. 7 and 8. On the front of the card will be a space to receive a small photograph f, Fig. 8, and at the side is a space f' on which are printed the words "From" and "To", and blank spaces on which will be written the machine letter and membership number of the person sending the photo-card, and the machine letter and membership number of the person intended to receive the card. On the back of the card, as shown in Fig. 7, are printed the words "From" and "To", and in the blank spaces will be written the city and State from and to which the photo-card is sent.

It will be assumed that member 12 of machine B in New York city desires to send his photo-card to member 25 of machine A in Pittsburgh. The photo-card will accordingly be filled out as shown in Figs. 7 and 8. When the operator of machine A in Pittsburgh receives the photo-card he places a notification card G, Fig. 12, in that pigeon-hole 37 which is numbered 25, in machine A, and also places the photo-card on the drum d in its proper pocket. When member A of machine 25 examines his pigeon-hole or box he removes the notification card G and presents it to the operator, who will then operate the machine to bring the photo-card into view through the openings 2 and 17, so that the member can see the picture of the person who is communicating with him. After this is done the operator returns the photo-card to the sender.

It is to be understood that a direction book will be given to each member of a machine, in which book will be listed all the different cities having machines, their numbers and the colors of buttons, and other necessary information.

Having thus described my invention, I claim as new and desire to secure by Letters Patent:

1. A machine of the class described comprising a cabinet having a view opening, a pocket drum mounted in the cabinet, means for rotatably and axially moving the drum to bring any desired pocket in registry with the view opening, and a scene element disposed between the view opening and drum and having a slot therein through which any desired pocket can be seen.

2. A machine of the class described comprising a cabinet having a single view opening, a movable element having two sets of card-holding pockets, the pockets having designations, and means for moving the element in two directions at right angles to each other for bringing any pocket of either set in register with the view opening, and indicating means exterior of the cabinet and having designations corresponding with the designations of the pockets.

3. A machine of the class described comprising a cabinet having a single view opening, a shaft therein, a drum formed of sections and keyed to and slidable on the shaft, 5 each section of the drum being provided with pockets having designations, and separate means disposed outside the cabinet and connected with the drum for axially and rotatably moving the latter to bring any 10 pocket of either section of the drum into registry with the view opening, the means for rotating the drum having designations corresponding with the designations of the pockets.
- 15 4. A machine of the class described comprising a cabinet having a view opening, a shaft mounted in the cabinet, a drum having a series of pockets and mounted on the shaft to turn therewith and movable axially 20 thereon, the pockets having designations, an index wheel connected with the shaft and located outside the cabinet and having designations corresponding with the designations of the pockets, whereby the wheel is turned 25 to bring any desired pocket in alinement with the view opening, means for locking the wheel against movement, and means for axially shifting the drum with respect to the view opening.
- 30 5. A machine of the class described comprising a cabinet having a view opening, a scene in the cabinet having a view slot, a carrier movably mounted in the cabinet and having article-containing pockets adapted to 35 be brought into alinement with the slot, a lamp for illuminating the scene, means for moving the said carrier, and a switch automatically closed by the movement of the carrier to position with a pocket in registry 40 with the slot.
6. In a machine of the class described, a casing having a view opening, a drum mounted in the casing and having one end of its shaft projecting outside of the casing, said drum having card holding means on its 45 periphery, an indexing wheel secured to the projecting end of the shaft and provided with apertures, an arm loose on the shaft outside of the indexing wheel and having an eye at its end, and a pin slidably mounted in 50 the eye of the arm and adapted to engage the apertures of the said wheel.
7. In a machine of the class described, a casing having a view opening, a drum mounted in the casing and having one end 55 of its shaft projecting outside of the casing, said drum having card holding means on its periphery, an apertured indexing wheel secured to the projecting end of the drum shaft, a fixed member having an aperture 60 adapted to register with the apertures of the indexing wheel, an arm loosely mounted on the projecting end of the said shaft, and a pin slidably mounted on the arm and adapted to engage an aperture of the indexing 65 wheel and the aperture of said member.
8. In a machine of the class described, a casing having a view opening, a revoluble and slidable drum mounted in the casing and having two sets of card holding means 70 on its periphery, a scene in the casing and having a slot registering with the view opening of the casing, a rocking arm engaging the hub of the drum to slide the drum and provided with a contact, an electric current, 75 a lamp in the circuit, and contacts on the casing and with which the contact of the rocking arm is adapted to engage.

CARL J. WITZORECK.
